J. BORGE.

INCINERATOR.

APPLICATION FILED APR. 6, 1916. RENEWED JAN. 11, 1918.

1,275,651.

Patented Aug. 13, 1918.

UNITED STATES PATENT OFFICE.

JOHN BORGE, OF NEW YORK, N. Y., ASSIGNOR TO BORGE INCINERATOR CORPORATION, OF NEW YORK, N. Y., A CORPORATION OF NEW YORK.

INCINERATOR.

1,275,651.

Specification of Letters Patent. Patented Aug. 13, 1918.

Application filed April 6, 1916, Serial No. 39,299. Renewed January 11, 1918. Serial No. 211,454.

To all whom it may concern:

- Be it known that I, JOHN BORGE, a subject of the King of Norway, and a resident of the city of New York, county of Kings, and 5 State of New York, and whose post-office address is Flatiron Building, New York city, have invented a new and useful Improvement in Incinerators, of which the following is a specification.
- 10 The object of my invention is to provide a simple, economical and durable incinerator, which will easily incinerate all the garbage or other material deposited in it at a minimum expense, and without objectionable gases or other resulting products. This 15 object is accomplished by my invention, one embodiment of which is hereinafter more particularly set forth, and shown in the accompanying drawings, in which—
- 20 Figure 1 is a sectional perspective view, showing an incinerator embodying my invention;

Figs. 2, 3 and 4 are sectional views taken on the lines 2—2, 3—3 and 4—4 respectively, 25 looking in the direction of the arrows.

Throughout the various views of the drawings, similar reference characters designate similar parts.

My improved incinerator 1 has a top 2, a 30 back 3, a front 4, and sides 5, as well as a bottom 6, all of which are preferably made of refractory material such as fire clay, silica, or similar material, which is surrounded by air chambers formed between 35 these parts (except the bottom 6) and the sheet iron protector 7. These parts are held together by any suitable means as angle iron corner stays 8.

The top 2 has a central charging opening 9 40 which is surmounted by a cap 10, said cap being composed of a hinged door 11 and frame 15, said door 11 having a handle 12, by which it may be opened and closed, and this door is hinged on a suitable rod 13 45 mounted on ears 14 which extend from the frame 15. This door is preferably inclined, as shown, and constitutes a charging door. Below this door is the garbage chamber 16, which extends from the door 11 to the dumping grate 17 at the bottom, and at its rear 50 it is bounded by the vertical partition 18, which is made of the same material as the lining, or any other suitable material. This partition 18 preferably extends to the floor 55 6 and has an opening 19 through which the

furnace gases may escape, as shown. The space between the rear wall 3 and the partition 18 forms a flue which may be connected through the opening 20 with any suitable pipe for taking off the waste gases. 60

The front of the chamber 16 is provided with a vertical partition 21 of the same material as the lining which has its lower end adjacent the dumping grate 17, and its upper end at the top 2. The upper end is recessed at 22, so as to permit the waste gaseous products to escape, and near its lower end it is provided with a number of vertical slots 23 through which flames may play upon the garbage in the manner described 70 below.

Opposite the slots 23 are corresponding openings 24 in the front 4, through which flames are played from the burners 25, which receive their gas or other fuel from a 75 suitable main 26.

Below the main 26, and at any convenient location, preferably as shown, is placed the ashpit door 27, mounted in the conventional way on hinges 28 which extend from the 80 door frame 29.

In view of the foregoing, the operation of my improved incinerator will be readily understood. The garbage to be incinerated is placed in the chamber 16 after the charging 85 door 11 is raised, and when this garbage is in place, this door is closed and the burners are then lighted and the flames played upon this garbage through the slots 23, thereby heating the same and driving off the volatile products, and drying the non-volatile products, and burning the same, so that no residue remains except ashes upon the grate 17, which ashes may be dumped in the usual manner, and removed through the doorway 95 at the bottom. When the volatile products are driven off the garbage, they pass first vertically and then horizontally through the opening 22 and then downwardly between the partition 21 and the front 4, and finally 100 outwardly through the ashpit above the bottom 6 and opening 19 to the flue behind the partition 18, and thence, as indicated, through the opening 20. The flames playing upon these descending gases as well as 105 the garbage, and the heat of the walls of the flues, complete the combustion of any unconsumed gases and superheat the vapors or steam, so that when the products of vaporization and the products of combustion pass 110

through the opening 20, they are harmless and not objectionable.

While I have shown and described one embodiment of my invention, it is obvious that it is not restricted thereto, but is broad enough to cover all structures that come within the scope of the appended claim.

Having thus described my invention, what I claim is:—

- 10 In a device of the class described, a chamber having a top, a bottom, a pair of side walls, a front wall and a rear wall, a pair of vertical partitions extending from side wall to side wall within the chamber forming a 15 garbage receiving chamber between them and also forming flues between them and the front and rear walls respectively, the top having an opening leading to the

garbage chamber, the front partition terminating above the bottom of the furnace and 20 having an opening adjacent its upper end, a garbage supporting grating extending between the partitions, the front partition being provided with a grated portion, the front wall having openings directed toward the 25 grated portion in the front partition, burners adapted to force flames through the openings in the front wall and through the grated portion of the front partition, the rear partition having an opening adjacent 30 its lower end, leading into the rear flue and the rear wall having an opening adjacent its upper end.

Signed at the city, county, and State of New York, this 29th day of March, 1916. 35
JOHN BORGE.
